UNITED STATES PATENT OFFICE.

PAUL G. ANDRES, OF ST. CHARLES, ILLINOIS, ASSIGNOR, BY MESNE ASSIGNMENTS, TO UNITED REPRODUCERS CORPORATION, OF ST. CHARLES, ILLINOIS, A CORPORATION OF NEW JERSEY.

SOUND-REGENERATING DEVICE.

Application filed December 18, 1926. Serial No. 155,602.

The present invention relates to devices for effecting sound reproductions.

Among the objects of the invention is to provide a novel sound regenerating device or 5 a device, such as an electro-magnetic device, adapted for the conversion of energies, as mechanical energy to electrical or electro-magnetic energy or vice versa, for the reproduction of sound. This novel invention is 10 adapted for use in connection with telephone receivers, radio loud speaker horns or cones or other like and similar diaphragmatic sound emitting and amplifying means, pick-up devices for talking machines or phonographs, 15 and the like. In the case of the latter the mechanical vibrations derived from the undulations of a phonograph record may be transmitted to an armature of an electro-magnetic device acting as a generator for effecting variations in the circuit thereof in 20 consonance or concordance with the initiatory vibrations or original productions, so that such variations, whether amplified or not, may be effective in a receiver of the telephone 25 or loud speaker type for reproduction of sound. In the other cases, the audio frequency electrical or electro-magnetic energy from a radio receiving device or on the receiving end of a telephone line, may be converted 30 through the electro-magnetic device, acting as a motor, into mechanical vibrations and energies for actuating a diaphragmatic sound emitting means. The invention comprehends the transmission of the energies at 35 the locus of conversion in a different direction than heretofore with a component relative movement and with a change of the moment of force to the end of augmenting the actuating force whereby those frequencies 40 which are not at the fundamental points of the device, may be strengthened and raised from the valleys toward the peaks of the fundamental frequencies or harmonics thereof. In this way the whole audible range of 45 frequencies may be made substantially uniform in amplitude and volume.

The invention, in a specific embodiment thereof, attains such by the disposing of the vibratory elements, such as the actuating connection 50 between the armature of the electro-magnetic and a diaphragmatic sound emitting means, and an armature connected thereto at an acute angle to each other. This angle may be determined for obtaining the best de-

sired results and dependent upon the load of 55 the diaphragmatic means, such as a cone, or diaphragm of a receiver. Heretofore, the actuating rod or wire was directed substantially at right angles to the plane of the armature. In this invention the rod or wire extends 60 at an acute angle to such plane so that a greater force may be transmitted to the cone or diaphragm, particularly at those frequencies which are not fundamental to the device and which, owing to the load or inertia 65 tending to dampen such frequencies, such that the greater force so applied will give the sound emitting surface the full and desired amplitudes and hence a more uniform volume 70 of sound reproduction. At the fundamental frequency points, the load or inertia of the device will not dampen such frequencies, since the device operates freely with the desired volume at such points.

Another object of the invention is to provide a unitary assembly, such as the coils, armature and pole pieces or shoes, adapted for ready attaching or securing to or detachment from a permanent magnet, preferably at the poles thereof, and to so dispose 75 the assembly with the parts thereof at an angle, preferably an acute angle, to the plane 80 of the permanent magnet. This affords for connecting the actuating means or element, such as the actuating rod or wire, so that it 85 may extend laterally from the device, as referred to the magnet, yet be connected to the armature at an acute angle thereto so that the rod or wire may receive the desired increased 90 forces or stresses at the non-fundamental points of the frequencies reproduced. In a specific embodiment of the invention, the assembly is preferably carried upon a mounting 95 securable to the magnet and holding the coils, shoes and armature at the desired angle to the plane of the magnet.

The invention also comprehends, as a part thereof, the idea of means for supporting the armature in vibratory position relative to the coils and polar shoes or pieces, and be adapted 100 to yield to such movements of the armature but to restore it to normal or central or medial position. In a specific embodiment, such restoring means is in the form of a torsion member or rod carried by the mounting or 105 supporting means of the unitary assembly and connected to the armature such that the rod may have torsional yield or resiliency

when the armature is vibrated, yet readily restore the armature to its original and normal position. By so restoring the armature, the latter will not be carried to any pole and 5 adhere thereto, but may be maintained in balanced or neutral position relative thereto.

The invention comprehends other features, advantages, capabilities and objects as will later appear and are inherently possessed by 10 the invention.

Referring to the drawing, Fig. 1 is a view in elevation of a device constructed in accordance with the invention.

Fig. 2 is a vertical sectional view taken in a 15 plane represented by line 2—2 in Fig. 1 of the drawings.

Fig. 3 is a top plan view or end view of the device shown in Fig. 1.

Fig. 4 is a transverse sectional view taken 20 in a plane represented by line 4—4 in Fig. 2 of the drawings.

And, Fig. 5 is a transverse sectional view taken in an inclined plane represented by line 5—5 in Fig. 2 of the drawings.

Referring now more in detail to the drawing 25 the embodiment selected to illustrate the invention is shown as included in an electromagnetic device comprising a permanent magnet 1 having spaced poles 2 and 3 to which 30 may be secured an assembly of electro-magnetic members. Such assembly comprises a mounting having a transverse non-magnetic plate 4 apertured at the ends thereof for the passage of securing screws 5 and 6 threaded 35 into flanges 7 and 8 of supporting plates 9 and 10 extending into the space between the poles 2 and 3 and in engagement with the inner surfaces thereof, as clearly shown in Figs. 3 and 4 of the drawings. The supporting 40 members 9 and 10, together with their flanges 7 and 8 are preferably of non-magnetic material. It will be apparent from the above 45 that the poles 2 and 3 of the permanent magnet occupy the spaces between the screws 5 and 6 and the supporting plates 9 and 10, and that the whole assembly may be held securely 50 in place by a suitable tightening of the screws 5 and 6.

To the inner surfaces of the supporting 55 plates 9 and 10 are located magnetic pole pieces or shoes 11 and 12 and 13 and 14 which are preferably U-shaped with a leg 15 or 16 or 17 or 18 respectively of these pieces, in contact with the inner faces of the plates 9 and 10 and with the other legs 19 or 20 or 21 or 22 spaced therefrom and located in the space between the poles 2 and 3 of the permanent magnet. 60 These pole pieces are preferably held in place by holding plates 23 and 24 engaging with the legs 15 and 16, and 17 and 18, and by means of screws 25 and 26 passing through suitable apertures provided in supporting plates 9 and 10 and threaded into holding plates 23 and 24, as clearly shown in Fig. 5 of the drawings.

Surrounding the legs 19, 20, 21 and 22 are solenoids or electrical coils 26, 27, 28 and 29, these coils engaging the legs with sufficient friction to be held properly in place as shown upon the drawings. These coils are preferably connected in series in an electrical circuit with the terminals passing to binding posts 30 and 31 mounted upon the cross member 4. Spacing rods or bars 32, 33 and 34 may be secured at their ends to the supporting 75 plates 9 and 10 in order to hold the same in proper spaced relation and to form a rigid unitary assembly.

Within the space between the ends of the legs 19, 20, 21 and 22 and also between the 80 coils, is mounted an armature 35 which may be provided with an extension 36 secured into an aperture or slot in a torsion rod or restoring element 37 having its ends 38 and 39 anchored in the side supporting plates 9 and 10, 85 as clearly shown in Figs. 3 and 4 of the drawings. At the other side of the armature 35 may be provided an extension 40 to which is secured an end of an actuating rod or wire 41, which may be suitably threaded to receive 90 securing elements (not shown) for holding a cone or other diaphragmatic sound emitting means.

It will be noted from the drawing and 95 above description that the pole pieces or shoes 11, 12, 13 and 14, as also the coils 26, 27, 28 and 29, and the armature 35, are disposed at an acute angle to the plane of the permanent magnet 1. It will also be clear that the actuating rod or wire 41 is also connected to the 100 armature at an acute angle to the plane of the armature. By disposing the parts in this relation, the vibratory movements of the armature may be transmitted with a component movement to the rod 41 and in a direction 105 along the axis thereof. In this way a greater force may be delivered along the rod and the means to be actuated thereby, with the effect of strengthening the particular vibrations or frequencies which are not at the fundamental 110 points of the device, so that they may be raised in amplitude so as to be substantially the same as the frequencies at the fundamental points. As the armature vibrates, the portion of the rod 37 connected to it will have a sufficient 115 amount of yield or resiliency so as to permit such armature to properly vibrate, but yet quickly restore the armature to its central or normal position and hold it there to prevent the armature from being drawn into contact with any of the legs, 19 or 20 or 21 or 22 of the polar pieces.

While the invention has been shown in an embodiment for converting electric or electrical energy into mechanical energy for vibrating a cone or diaphragm, it is to be understood that the invention is also applicable to a pick-up device on a phonograph or the like for converting mechanical energy to electrical or electro-magnetic 125 130

energy. In the latter case, the rod 41 may be in the form of a stylus which may operate in a groove of a record, having hill and dale undulations. In the event of using a record with grooves having lateral undulations, the stylus would be disposed at right angles to the present position of the rod 41, but be at an acute angle to the armature 35. In the case of a pick-up device, the 10 mechanical vibrations received or derived from the phonograph record will be transmitted to the armature 35 which will set up variations in the circuit of the electrical coils or solenoids and the circuit thereof which 15 may be connected to a receiving electro-magnetic device or a loud speaker horn or cone or even a telephone receiver of a telephone line, or of head pieces, and if desired, the same may be amplified by passing the current through a suitable radio audio amplifying device.

While I have herein described and upon the drawings shown an illustrative embodiment of the invention, it is to be understood 25 that the invention is not limited thereto but may comprehend other constructions, details and arrangements of parts without departing from the spirit thereof.

Having thus disclosed the invention, I 30 claim:

1. In a sound regenerating device, an electro-magnetic means having a vibratory armature associated therewith, a torsion means connected to said armature whereby 35 the armature may vibrate, and an actuating means connected to said armature and disposed to transmit an actuating force in a direction at an acute angle to the plane of the armature.
2. In a sound regenerating device, an electro-magnetic means having a vibratory armature associated therewith, a torsion rod connected to an end of said armature, and an actuating element connected to the other end 45 of said armature and at an acute angle to the plane thereof, said element being adapted to actuate a diaphragmatic sound emitting means.
3. In a sound regenerating device, an electro-magnetic means having a vibratory armature associated therewith, a torsion restoring means connected to said armature and adapted to yield to vibratory movements of the armature and to restore the armature to 55 normal central position, and an actuating means connected to said armature and so arranged to transmit an actuating force in a direction at an acute angle to the plane of said armature.
4. An electro-magnetic device adapted for conversion of energies for the reproduction of sound, comprising a permanent magnet having polar pieces, coils, cores associated with said pieces, an armature vibratably supported to cooperate with said cores, said

pieces, coils, cores and armature being arranged as a unit and disposed at an acute angle to the plane of the permanent magnet, and an actuating element connected to said armature.

5. An electro-magnetic device adapted for conversion of energies for the reproduction of sound, comprising a permanent magnet having polar pieces, coils, said pieces having poles associated with said permanent magnet 75 and poles acting as cores for said coils, an armature vibratably associated with the latter poles, said pieces, coils and armature being disposed at an acute angle to the plane of said magnet, and an actuating means associated with said armature for transmission of vibrations to or from the same.

6. An electro-magnetic device adapted for conversion of energies for the reproduction of sound, comprising a permanent magnet 85 having polar pieces, coils, said pieces having poles associated with said permanent magnet and poles acting as cores for said coils, an armature vibratably associated with the latter poles, said pieces, coils and armature 90 being disposed at an acute angle to the plane of said magnet, and an actuating element connected to said armature at an acute angle thereto.

7. An electro-magnetic device adapted for conversion of energies for the reproduction of sound, comprising a permanent magnet having polar pieces, coils, said pieces having poles associated with said permanent magnet and poles acting as cores for said coils, an armature vibratably associated with the latter poles, said pieces, coils and armature being disposed at an acute angle to the plane of said magnet, a restoring means carried by 100 said magnet and connected to said armature and adapted to yield to vibrations of said armature and to restore the same to normal central position, and an actuating means associated with said armature for transmission of vibrations to or from the same.

8. An electro-magnetic device adapted for conversion of energies for the reproduction of sound, comprising a permanent magnet having poles, a unitary assembly detachably associated with said magnet at the poles thereof and comprising polar shoes, coils associated with said shoes, an armature vibratably associated with said coils and shoes, and an actuating means associated with said armature for transmission of vibrations to or from the same.

9. An electro-magnetic device adapted for conversion of energies for the reproduction of sound, comprising a permanent magnet having poles, a unitary assembly detachably associated with said magnet at the poles thereof and comprising polar shoes, coils associated with said shoes, an armature vibratably associated with said coils and shoes, said assembly being disposed with said shoes,

coils and armature at an acute angle to the plane of said magnet, and an actuating means associated with said armature for transmission of vibrations to or from the same.

- 5 10. An electro-magnetic device adapted for conversion of energies for the reproduction of sound, comprising a permanent magnet having poles, a unitary assembly detachably associated with said magnet at the poles thereof and comprising polar shoes, coils associated with said shoes, an armature vibratably associated with said coils and shoes, said assembly being disposed with said shoes, coils and armature at an acute angle to the plane of said magnet, and an actuating element connected to said armature at an acute angle thereto.

11. An electro-magnetic device adapted for conversion of energies for the reproduction of sound, comprising a permanent magnet having poles, a unitary assembly detachably associated with said magnet at the poles thereof and comprising polar shoes, coils associated with said shoes, an armature vibratably associated with said coils and shoes, said assembly being disposed with said shoes, coils and armature at an acute angle to the plane of said magnet, a restoring member carried by said assembly and connected to said armature, said member being yieldable to vibratory movements of said armature and capable of restoring the armature to normal or mean position relative to said coils and shoes, and an actuating means associated with said armature for transmission of vibrations to or from the same.

12. An electro-magnetic device adapted for conversion of energies for the reproduction of sound, comprising a permanent magnet having poles, a unitary assembly detachably associated with said magnet at the poles thereof and comprising polar shoes, coils associated with said shoes, an armature vibratably associated with said coils and shoes, said assembly being disposed with said shoes, coils and armature at an acute angle to the plane of said magnet, a torsion member comprised in said assembly and being connected to an end of said armature, said member being adapted to yield to vibratory movements of said armature and capable of restoring the armature to normal medial position rela-

tive to said coils and shoes, and an actuating element connected to said armature at an acute angle thereto.

55

13. An electro-magnetic device adapted for conversion of energies for the reproduction of sound, comprising a permanent magnet having poles, a mounting adapted for securing to said poles and having means for holding polar shoes in given relation to said poles, coils carried by said shoes, and an armature on said supporting means and vibratably located between said coils and shoes, and an actuating means associated with said armature for transmission of vibrations to or from the same.

60

65

14. An electro-magnetic device adapted for conversion of energies for the reproduction of sound, comprising a permanent magnet having poles, a mounting adapted for securing to said poles and having means for holding polar shoes at an acute angle to the plane of said magnet, coils carried by said shoes, and an armature on said supporting means and vibratably located between said coils and shoes, said coils and armature being disposed at an acute angle to the plane of said magnet, and an actuating means associated with said armature for transmission of vibrations to or from the same.

70

75

80

15. An electro-magnetic device adapted for conversion of energies for the reproduction of sound, comprising a permanent magnet having poles, a mounting adapted for securing to said poles and having means for holding polar shoes at an acute angle to the plane of said magnet, coils carried by said shoes, and an armature on said supporting means and vibratably located between said coils and shoes, a restoring member carried by said supporting means and connected to said armature, said member being capable of yielding to vibratory movements of said armature and to restore said armature to normal central position relative to said coils and shoes, said coils and armature being disposed at an acute angle to the plane of said magnet, and an actuating means associated with said armature for transmission of vibrations to or from the same.
